UNITED STATES PATENT OFFICE.

LOUIS LERIO, OF MOBILE, ALABAMA.

TURPENTINE-CUP.

1,211,189.

Specification of Letters Patent. Patented Jan. 2, 1917.

Application filed September 27, 1915. Serial No. 52,892.

To all whom it may concern:

Be it known that I, LOUIS LERIO, a citizen of the United States, residing at Mobile, in the county of Mobile and State of Alabama, 5 have invented certain new and useful Improvements in Turpentine-Cups, of which the following is a specification.

This invention relates to certain new and useful improvements in turpentine cups.

10 Heretofore cups have generally been made of galvanized iron which have been found to be unsatisfactory for the reason that after a short period of use the cup begins to corrode on the inside, causing a serious discoloration of the gum, and when the same is distilled this discoloration causes a very serious lowering of the grades of rosin. An attempt has been made to overcome this objection by making a cup of clay, but this 15 has been found objectionable for the reason that although it has no effect on the grades of rosin its weight is from three to four times as much as that of a galvanized iron cup, and, furthermore, is very easily broken.

20 I have found from experience that all of the objections to the known forms of cups can be obviated by providing a cup with a wooden lining.

25 The invention, in its preferred form, is clearly illustrated in the accompanying drawings, which, with the numerals of reference marked thereon, form a part of this specification, and in which—

30 Figure 1 is a perspective view of my improved cup. Fig. 2 is a longitudinal section on the line 2—2 of Fig. 1 looking in the direction of the arrows. Fig. 3 is a cross section on the line 3—3 of Fig. 2 looking in the direction of the arrows. Fig. 4 is a view 35 of the blank from which the body portion of the lining is formed. Fig. 5 is a face view of one of the end portions of the lining.

35 Like numerals of reference indicate like parts throughout the different views.

40 Referring to the drawings, 1 designates the body portion of the cup, of galvanized iron or any other suitable material, comprising the sides and bottom and the ends 2. These ends may be connected to the body 45 portion in any suitable manner and, in fact, the body portion of the cup may be formed in a variety of ways.

45 In order to protect the metal of the body portion and ends of the cup from corrosion

I line the same with wood, preferably a 55 veneer that is capable of being bent into the desired form. In Fig. 4 I have shown a blank 3 of wood of a character suitable for the purpose having its end portions chamfered, as at 4. This blank is designed to be 60 placed within the cup proper and then bent into a shape or form corresponding with that of the cup and when in place the end portions 5 of similar material chamfered around their edges, as seen at 6, are placed 65 in position, the chamfered edges 6 of the end portions of the lining fitting the chamfered portions 4 of the blank 3 forming the lining proper and then the upper edges of the opposite sides of the body portion 1 are 70 bent over, as at 7, inward upon the top edges of the blank 3 and the top edges of the ends 2 of the cup proper are bent over inward upon the top edges of the ends 5 of the lining, by which means the ends 5 of the lining 75 are forced downward into close contact with the adjacent edges of the blank 3, the chamfered edges 4 and 6 acting wedge-like to form a tight joint. The parts are thus all firmly held together and the wood lining 80 serves to protect the metallic portion of the cup and keep the gum from coming in contact with the metal portion and, hence, all corrosion and discoloration is obviated. The wood is not affected by the gum, but 85 if it ever should become necessary to replace the lining or any portion thereof, all that it will be necessary to do is to turn back the bent-over top edges or flanges 7 and 8 of the body portion and ends of the cup proper and 90 remove the lining and then replace it by another.

95 The wood lining does not add materially to the cost or weight of the cup, but increases its life many times, besides overcoming all heretofore known objections to metallic cups.

100 Modifications in detail may be resorted to without departing from the spirit of the invention or sacrificing any of its advantages.

105 Another advantage resulting from the use of the wood lining is that it saves considerable loss as it prevents evaporation of the turpentine from the gum, the wood lining being a non-conductor of heat and thus the loss by evaporation is reduced to the minimum.

What I claim as new is:—
A metallic turpentine cup and a lining
therefor formed of a single sheet of bend-
able material fitted to the sides and bottom
5 of said cup, and separate end portions with
the adjacent edges of the body and end por-
tions of the lining chamfered, the upper
edges of the sides and ends of the cup being

bent over the top edges of the sides and
ends of the lining.

In testimony whereof I affix my signature
in presence of two witnesses.

LOUIS LERIO.
